UNITED STATES PATENT OFFICE.

CHARLES FREDERICK MOORE, OF NORWICH, CONNECTICUT, ASSIGNOR TO THE SCHWARZENBACH HUBER CO., OF WEST HOBOKEN, NEW JERSEY, A CORPORATION OF NEW JERSEY.

TENSION DEVICE FOR SHUTTLES.

Application filed June 26, 1924. Serial No. 722,533.

To all whom it may concern:

Be it known that I, CHARLES FREDERICK MOORE, a citizen of the United States, and a resident of Norwich, in the county of New London and State Connecticut, have invented a new and Improved Tension Device for Shuttles, of which the following is a full, clear, and exact description.

This invention relates to improvements in shuttles, and particularly to an improved tension device and guide for the thread, and has for an object to provide an effective simplified construction which will automatically provide the desired tension as the shuttle moves.

Another object is to provide a tension device which begins to function automatically as soon as the thread is placed in operative position.

20 A still further object is to provide an automatic threading structure and tension device whereby in machines using automatic shuttles, the thread will be automatically threaded and simultaneously brought under the proper tension.

In the accompanying drawing—

Figure 1 is a fragmentary top plan view showing one end of a shuttle with an embodiment of the invention applied thereto.

30 Figure 2 is a edge view of the structure shown in Figure 1.

Figure 3 is a sectional view through Figure 1 approximately on line 3—3.

Figure 4 is a transverse sectional view through Figure 2 approximately on line 4—4.

Figure 5 is a transverse sectional view through Figure 2 approximately on line 5—5.

40 Figure 6 is a transverse sectional view through Figure 2 approximately on line 6—6.

Figure 7 is a longitudinal horizontal sectional view through Figure 3 approximately on line 7—7.

Figure 8 is a perspective view of the automatic threading and guiding structure embodying certain features of the invention.

50 Figure 9 is a side elevation of the tension device shown in Figure 7.

Referring to the accompanying drawing by numerals, 1 indicates a shuttle, which is of the usual type and cut away at the front for receiving a thread guiding structure 2 and a tension device 3. The thread guiding

structure is locked in position by any suitable means, as, for instance, a screw 4, while the tension device 3 is held in place by any suitable means, as, for instance, wood screws 5. The thread guiding structure 2 may be 60 made in one piece or in a number of pieces, but when completed will appear as shown in the drawing, particularly in Figure 8. From this figure, it will be noted that this thread guide or automatic threading device 65 is formed with a top 6 rounded to conform somewhat to the shape of the end of the shuttle and provided with turned down members 7 and 8, member 8 acting to guide the thread into the passageway 9, while the 70 member 7 acts to guide the thread to the tension device 3. As it moves over the tension device 3, the thread passes along the end 10 out through the side slot 11 formed in the shuttle 1, and as it moves through this slot 75 it always moves downwardly and out past the posts 12 and 13. Referring to Figures 4 and 5, it will be noted that the turned down member 8 extends slightly below the upwardly extending section 14, whereby the 80 thread will ordinarily be held against return movement, as the thread usually operates slightly above the top of member 14. A pin or reduced section 15 extends downwardly from the top 6 and forms a 85 guiding post, as shown in Figure 7, for guiding the thread through the opening 9 to the tension device 3. From Figure 7, it will be noted that the post 15 extends downwardly substantially centrally of the tension device 3, and extends through the bottom of plate 17 as illustrated in Figure 3.

The tension device 3 is provided with an upstanding plate 16, which receives the screws 5, and a horizontal plate 17, from which a forwardly extending bracket 18 extends and also from which the tension arms 19, 20 and 21 extend, each of said arms being provided with a hook 22. A shaft 23 is rotatably mounted in the bracket 18, this shaft being also journaled in an auxiliary bracket 24 upstanding from one end of the plate 17. This shaft receives a tubular member 25, from which projects the tension fingers 26 and 27, said fingers being preferably round in cross section and are the length to project beyond the hook 22 when fully depressed. When this has been done, as indicated in dotted lines in Figure 9, the open 100 end of the hook 22 is closed but the thread 105 110

is allowed to pass freely through the eye formed thereby. In order to produce a proper tension on the thread, a resilient member 28 is connected at one end to the tubular member 25 and has the opposite end held in a given position by the screw 29. The member 28 has been shown as a short section of rubber which has been found to be extremely desirable, though a metallic spring or other elastic member might be substituted without departing from the spirit of the invention. In case a greater tension is desired, the member 26 would be shortened or given another turn around the screw 29. When the parts are in operative position, the thread and associated parts will assume the various positions shown in Figure 7, and in this position the thread may be pulled through to the right or the left as viewed in this figure and properly feed out of the shuttle while being continually maintained under

tension by the respective fingers 26 and 27 and associated parts. These fingers also act to a large extent as take-up for taking up slack thread.

25

I claim:

A take-up and tension device for shuttles, comprising means for guiding the thread over a certain path as it is pulled so that it will automatically be fitted into the correct position; said means including a pair of overlapping members forming a passageway, said members at the point of overlapping being spaced apart sufficiently to permit the thread to pass therethrough, a plurality of spaced stationary arms having hooks arranged adjacent said thread guiding means, a plurality of fingers co-acting with said hooks, and resilient means for causing said fingers to press the thread so that it will frictionally engage said hooks.

CHARLES FREDERICK MOORE.
